US0D1076517S

(12) **United States Design Patent** (10) **Patent No.:** **US D1,076,517 S**
(45) **Date of Patent:** **** May 27, 2025**

(54) **DISPLAY ASSEMBLY**

- (71) Applicant: **ALL PLASTIC, INC.**, Rancho Cordova, CA (US)
- (72) Inventors: **William Thomas Smith**, Fair Oaks, CA (US); **Cheryl Ann Smith**, Fair Oaks, CA (US)
- (73) Assignee: **ALL PLASTIC, INC.**, Rancho Cordova, CA (US)
- (**) Term: **15 Years**
- (21) Appl. No.: **29/805,310**
- (22) Filed: **Aug. 26, 2021**
- (51) **LOC (15) Cl.** **06-04**
- (52) **U.S. Cl.**
USPC **D6/672**
- (58) **Field of Classification Search**
USPC D6/657, 672, 675, 675.3, 675.4, 681,

CLAIM

The ornamental design for a display assembly, as shown and described.

DESCRIPTION

FIG. 1 is a perspective view of a display assembly in accordance with a first variant of said design;

FIG. 2 is a top plan view of the display assembly shown in FIG. 1;

FIG. 3 is a bottom plan view of the display assembly shown in FIG. 1;

FIG. 4 is a front view of the display assembly shown in FIG. 1;

FIG. 5 is a rear view of the display assembly shown in FIG. 1;

FIG. 6 is a right side view of the display assembly shown in FIG. 1;

FIG. 7 is a left side view of the display assembly shown in FIG. 1; and,

FIG. 8 is a further perspective view of the display assembly shown in FIG. 1, in which containers of the display assembly are shown.

The broken lines shown in the Figures are included for the purpose of illustrating environment and form no part of the claimed design. All surfaces not shown form no part of the claimed design. The shade lines in the Figures show contour and not surface ornamentation. The oblique line shading in the Figures shows a transparent surface and not surface ornamentation.

1 Claim, 8 Drawing Sheets
